UNITED STATES PATENT OFFICE.

WILLIAM A. LORENZ, OF HARTFORD, CONNECTICUT, ASSIGNOR TO UNION PAPER BAG MACHINE COMPANY, OF PHILADELPHIA, PENNSYLVANIA, A CORPORATION OF PENNSYLVANIA.

PAPER-BAG MACHINE.

SPECIFICATION forming part of Letters Patent No. 795,046, dated July 18, 1905.

Application filed November 9, 1903. Serial No. 180,325.

To all whom it may concern:

Be it known that I, WILLIAM A. LORENZ, a citizen of the United States, and a resident of Hartford, in the county of Hartford and State 5 of Connecticut, have invented certain new and useful Improvements in Paper-Bag Machines, of which the following is a full, clear, and exact specification.

The object of this invention is to provide 10 automatic mechanism for forming in the open or mouth end of the side tucks of bellows-sided paper bags or paper-bag blanks certain reversed folds which are shown and described in Letters Patent of the United States to H. M. 15 Farnsworth, No. 355,010, dated December 28, 1886, so that when the bag is opened for use these particular folds will turn outwardly instead of inwardly, and thus present a funnel-shaped mouth for the more ready reception 20 of the contents of the bag. These folds also assist in maintaining the mouth of the bag in an open condition. For this purpose the upper or mouth ends of the inwardly-tucked bellows plies of the blank are turned out- 25 wardly, the innermost bellows-fold lines being reversed and swung outwardly to positions approximately ninety degrees from their former positions. The machine of the present invention produces these folds by first turning 30 over one of the flat side walls of the bag or blank around a transversely-disposed defining edge, thereby opening the mouth ends of the tucked bellows plies into flattened triangular plies. Then a blade, herein designated as the 35 reversing-blade, is brought against the blank across the centers of the triangular plies into approximate coincidence with what were formerly the inner bellows-fold lines, upon which lines each of these triangles is then doubled 40 upon itself by the turning back of the doubled-over side wall, the reversing-blade serving to prevent the said fold-line from returning to its original position.

This invention may be embodied in an in- 45 dependent machine by providing it with a suitable driving mechanism and by providing means for feeding the blanks or bags to it in proper sequence and register; but I prefer to

embody the invention in a machine which operates in conjunction with mechanism for 50 folding the bottoms of paper bags from bellows-sided blanks, thus embodying in a single organization an automatic machine for rapidly manufacturing bellows-sided paper bags having these funnel-mouth folds. When thus 55 employed in such an organization, the machine of my present invention may perform its operations before the bottom of the bag has been formed, or it may, as herein shown, receive the bags after the bottom-forming 60 mechanism has completed the bottom folds, or both operations may be performed simultaneously.

Figure 1 of the drawings is a plan view of a machine embodying my present invention 65 with part of the top mechanism removed. Fig. 2 is a side view of the machine in section, taken on the line 2 2 of Fig. 1. Fig. 3 is a side view in section, taken partly on the line 3 3 of Fig. 1 and partly on the line 3^a 3^a of 70 Fig. 4. Fig. 4 is a plan view of a portion of the machine, partly in section, taken along the lines 4 4 and 4^a 4^a of Fig. 3. Fig. 5 is an end view of the top suction-box, taken in section on the line 5 5 of Fig. 2. Fig. 6 is a 75 plan view, and Figs. 7, 8, and 9 are side views, partly in section, showing portions of the folding devices of the machine in successive stages of operation upon the mouth of a paper bag or blank. Fig. 10 is a side view showing 80 a modified arrangement of portions of the folding devices. Figs. 11, 12, and 13 are perspective views of the mouth end of a bellows-sided bag-blank in successive stages of the folding operation. Fig. 11 shows the 85 blank before it has been folded. Fig. 12 shows an intermediate position of the fold, and Fig. 13 shows the completed funnel folds.

The organization of mechanism shown and described herein is adapted to be attached to 90 many of the well-known forms of paper-bag machines, the feed-rolls 18 and 19 being considered as equivalents or substitutes for the delivery-rolls of such paper-bag machines. The mechanism herein shown is driven by a 95 train of gears which may receive their mo-

tion from the pulley 17 or from the gear 25 by meshing that gear with a gear on the paper-bag machine to which it is connected. The feed-rolls 18 and 19 are mounted upon the shafts 20 and 21, journaled in bearings 22, 22, and are provided with gears 24 and 25, respectively, which mesh together. These shafts and bearings are supported in the uprights 26 and 27, secured upon a base 28. 10 The feed-roll 18 is pressed toward the roll 19 by means of springs 23 against the bearings 22. Motion is transmitted, by means of the gear 25, to the intermediate gear 29, which runs upon the stud 30 and transmits motion 15 to the gear 31, attached to the shaft 32, running in bearings 33 and 34, attached to the uprights 26 and 27, respectively. The rotating blank-support 35 is approximately cylindrical, having portions cut away in its periphery, as shown in Figs. 7 and 8, and it is carried by the shaft 32.

Between the feed-rolls 18 and 19 and the blank-support 35 is the guide-plate 36, which is curved upward at its inner end to an approximately tangential relation to the surface of the blank-support and is attached to the bar 37, supported by the uprights 26 and 27.

Above the blank-support is the suction-box 38, which serves to sustain the upper wall of the blank during the folding operation. It is supported by the brackets 39, secured to the uprights 26 and 27, and the lower or suction wall 40 follows the curvature of the cylindrical surface of the blank-support, with 30 an annular space between them for the passage of the blank, the said wall 40 being grooved throughout its length at 41, Fig. 5, to clear the grippers 51. This wall is also provided with perforations 42, communicating 35 with the interior of the box. Connection with suitable exhausting apparatus is made by the pipe 43, which may be provided with valve devices for cutting off connection with the box or for allowing communicating therewith at suitable intervals during the passage 40 of the blank through the machine like the devices shown and described in my Patent No. 591,175 of October 5, 1897.

The blank-support 35 carries one or more 50 sets of gripping and folding devices to which suitable movements are imparted as the blank-support rotates. The machine herein shown is provided with two sets of these devices; but I will describe but one of these sets, it being understood that the construction and mode of operation of the second set is similar thereto, and these devices alternate in their 55 operation upon the succeeding blanks.

The gripping device consists of a gripper 60 51, which may be bifurcated, as shown in Fig. 1, and is attached to a shaft 52, provided with an arm 53, carrying a roller or projection which is held against the fixed cam 54 by a spring 55. The cam 54 is supported by the bearing 33 and may be separate or may be

integral with another cam, as shown in the drawings.

Each of the two sets or sections of the blank-support is also provided with a folding suction-box 59, which rotates with the blank-support and operates to turn over one of the side walls of the blank. This suction-box 59 is of a substantially triangular cross-section in its central portion and has oppositely-disposed trunnions 60 journaled in the brackets 61, appurtenant to the blank-support 35, the common axis of the trunnions 60 being substantially in alignment with the defining edge 62, formed by the meeting of the outer surfaces of the upper and lower walls of the suction-box 59 and substantially coincident with the circle of rotation of the supporting-surface of the blank-support. This defining edge serves to locate and define the transverse line 99 of the blank, over which the lower ply thereof is folded to the form shown in Fig. 12. Each of the blank-holding sections of the blank-support may also be provided with a projecting ledge 44, extending to or toward the defining edge 62 of the suction-box. This ledge when employed serves to support the corresponding portion of the blank, and when it extends to the defining edge 62 of the suction-box its edge 45 supplements the action of the suction-box in defining the fold-line 99 of the blank; but this ledge may be dispensed with, as shown by the modified form of blank-support 71 in Fig. 10, in which case the defining of the transverse fold-line 99 is performed entirely by the defining edge 72 of the suction-box 73. In this modification also the upper wall of the suction-box is preferably curved in an arc substantially coinciding with the circle of the blank-support 71, so as to take the place of the projecting ledge 44 of the blank-support 35 in supporting the blank while the suction-box is in the position shown in Fig. 10.

The wall of the suction-box 59 is provided with perforations 63, communicating with its interior, and connection with the exhaust apparatus is made through the trunnions 60, which are made hollow and meet the pipes 64 at their ends. The pipes 64 are bent so as to clear the intervening parts and pass through the hub 47 of the blank-support into the shaft 32, which is made hollow and communicates, by means of the pipe 48, with the exhaust apparatus. These suction-pipes may also be provided with controlling-valve devices like those of my aforesaid Patent No. 591,175. Secured to one of the projections 60 of the suction-box 59 is the sector-pinion 65, which serves to rotate the box 59 at the proper moment by means of the sector-gear 66, pivotally supported on the blank-support 35 by the pin 68 and operated by the projection or roll 69, controlled by the cam-groove 70 on the face of the fixed cam 54. The pressure over the holes 63 of the suction-box 59 causes the

lower ply of the blank to adhere to the wall 58 of the box, and the motion of the box turns the rearward end of that lower ply around the defining edge 62, the upper ply being mean-
5 while sustained by the upper suction-box 38, and thus prevented from folding over with the lower ply.

Each blank-holding section of the blank-support is also provided with a reversing-
10 blade 74, mounted on an arm 75, which is pivoted on a stud 76 appurtenant to the blank-support. The arm 75 is provided with a stud or roll 77, running in the cam-groove 78 of the fixed cam 79. The defining edge of the
15 blade 74 is parallel with the defining edge 62 and is mounted to move toward and from that defining edge during the rotation of the blank-support, coöperating with the suction-boxes 38 and 39 to complete the funnel-mouth folds.

20 Just before the front end of the blank, which is held by the gripper 51, reaches the plate 89 the gripper is released to allow the blank to be delivered from the blank-support. At the same time the blank is held to the support by
25 the bifurcated pressing-sector 82, fixed to the rotating shaft 83, mounted in bearings 84 in the uprights 26 and 27, each bearing being pressed toward the blank-support 35 by a spring 85. Rotary motion is imparted to the
30 sector 82 by the gear 86 meshing into the large gear 31. The completed blank then passes over the plate 89 to the delivery-rolls 90 and 91, which may be provided with tapes 92 to carry the blanks away from the machine.

35 The consecutive operation of this machine is as follows: The blank B is delivered to the rolls 18 and 19 in approximately the condition shown in Fig. 11 and passes over the plate 36, being deflected upwardly thereby, and
40 thus directed tangentially to the surface of the blank-support 35. The leading end of the blank is gripped to the blank-support by means of the gripper 51. When the rear or mouth end of the blank arrives opposite the
45 upper suction-box 38, the air-pressure holds the upper wall of the blank in contact with the under surface 40 of the suction-box. The lower or folding suction-box 59 is then turned on the trunnions 60, the axes of which are ap-
50 proximately in alinement with the defining edge 62, thus turning downwardly and forwardly the lower wall of the blank which adheres to it around the edge 62, and thereby stretching open the mouth end of the blank,
55 as shown in Figs. 6, 7, and 12. Then the reversing-blade 74 is moved forward toward the defining edge 62, as shown in Fig. 8, against the fold-lines 99 of the blank. While the blade 74 remains in this position, the suction-
60 box 59 is turned back toward the blade 74, thereby returning the lower wall of the blank to its first position, as shown in Fig. 13, and doubling the triangular side folds upon themselves upon the fold-line 99 around the edge
65 of the blade 74, thus reversing the folds upon

that line and leaving it in substantial coincidence and alinement with the axes of the trunnions 60, and thereby forming on each side of the blank the two V-shaped funnel folds 98. The gripper 51 releases the forward end of
70 the blank just before reaching the plate 89, which plate guides the blank between the rolls 90 and 91, while the pressing-sectors 82 feed the blank forward. When the mouth end of the blank approaches the plate 89, the
75 funnel-defining blade 74 is gradually retracted, and the funnel folds are held together by the pressure of the sectors 82, being finally compressed by passing between the rolls 90 and 91 and the tapes 92 to approximately the
80 condition shown in Fig. 13, in which view, however, the blank is opened to a slight extent, so as to represent more clearly the character of the funnel folds produced by this operation.

85 The terms "upper," "lower," "right," "left," "forward," "backward," and similar terms denoting relative positions are herein used in their relative and not their absolute sense, inasmuch as many of the parts may be
90 reversed, inverted, or transposed in many ways that will be obvious to the mechanic or designer. The mechanism herein shown and described may also be modified as to dimensions, amplitude of movement, and in many
95 other obvious ways to suit different sizes of bags or to suit various conditions of service.

I claim as my invention—

1. Means for forming the described funnel folds in the mouth ends of bellows-sided bag-blanks, comprising a blank-support, a swinging suction-box having a defining edge, means for swinging the box to open the mouth end of the blank to form the preliminary triangular folds and to subsequently close the mouth end to form the funnel folds, and a reversing-blade mounted in the blank-support to coöperate in doubling the said triangular folds to form the said funnel folds.

100 2. Means for forming the described funnel folds in the mouth ends of bellows-sided bag-blanks, comprising a rotatable blank-support, a swinging suction-box having a defining edge, means for swinging the box to fold the rearward end of the lower ply in a forward direction to form the preliminary triangular folds and to subsequently fold it back to form the funnel folds, and a movable reversing-blade mounted to coöperate in doubling the said triangular folds to form the said funnel folds.

105 3. The combination of a rotatable blank-support, a suction-box mounted for oscillation on the blank-support and provided with a perforated suction-surface for holding and folding back a ply of the blank, and means for oscillating the suction-box while the blank-support is rotating.

110 4. The combination, in devices for forming the described triangular folds in the mouth ends of bellows-sided bag-blanks, of a rotata-

ble blank-support, and a suction-box mounted for oscillation on the blank-support on an axis transverse to the travel of the blank and provided with a fold-defining edge substantially in line with the axis of oscillation of the suction-box.

5. The combination, in devices for forming the described triangular folds in the mouth ends of bellows-sided bag-blanks, of a rotatable blank-support and a suction-box having a defining edge and mounted for oscillation on the blank-support, with its axis and defining edge substantially coincident with the circle of rotation of the blank-supporting surface 15 of the blank-support.

6. The combination, in devices for forming the described triangular folds in the mouth ends of bellows-sided bag-blanks, of a substantially cylindrical blank-support having a 20 recess in its periphery, and a suction-box mounted in the said recess for oscillation on an axis substantially coincident with the circle of the cylindrical surface of the blank-support.

25 7. The combination, in devices for forming the described triangular folds in the mouth ends of bellows-sided bag-blanks, of a substantially cylindrical blank-support having a recess in its periphery, and a suction-box having 30 a defining edge, and mounted for oscillation in the said recess, with its axis and defining edge substantially coincident with the circle of the cylindrical surface of the blank-support.

35 8. The combination of a rotatable blank-support, a suction-box mounted for oscillation on the blank-support and provided with a perforated suction-surface for holding and folding back a ply of the blank, and means for 40 oscillating the suction-box while the blank-support is rotating, the blank-support being provided with a supporting-ledge projecting over the suction-box toward the defining edge thereof.

45 9. The combination of a rotatable blank-support, a suction-box mounted for oscillation on the blank-support and provided with a perforated suction-surface for holding and folding back a ply of the blank, and means for 50 oscillating the suction-box while the blank-support is rotating, the blank-support being provided with a projecting ledge extending substantially to the defining edge of the suction-box and forming a supplemental defining edge.

55 10. The combination of a rotatable blank-support, a suction-box mounted for oscillation on the blank-support, and provided with a perforated suction-surface for holding and folding 60 back a ply of the blank to form flattened triangular folds, means for oscillating the suction-box while the blank-support is rotating, and means for doubling the said triangular folds to form the said funnel folds.

65 11. The combination, in devices for forming

the described funnel folds in the mouth ends of bellows-sided bag-blanks, of a rotatable blank-support, a suction-box mounted for oscillation on the blank-support and provided with a perforated suction-surface for holding 70 and folding back a ply of the blank to form flattened triangular folds, means for oscillating the suction-box while the blank-support is rotating, and means for doubling the said triangular folds to form the said funnel 75 folds, the blank-support being provided with a supporting-ledge projecting over the suction-box toward the defining edge thereof.

12. The combination, in devices for forming the described funnel folds in the mouth ends 80 of bellows-sided bag-blanks, of a rotatable blank-support, a suction-box mounted for oscillation on the blank-support and provided with a perforated suction-surface for holding and folding back a ply of the blank to form 85 flattened triangular folds, means for oscillating the suction-box while the blank-support is rotating, and means for doubling the said triangular folds to form the said funnel 90 folds, the blank-support being provided with a projecting ledge extending substantially to the defining edge of the suction-box, and forming a supplemental defining edge.

13. The combination, in devices for forming the described triangular folds in the mouth 95 ends of bellows-sided bag-blanks, of a rotatable blank-support, a stationary suction-box for sustaining the upper ply of the blank, a swinging suction-box mounted for oscillation on the blank-support, and provided with a 100 perforated suction-surface for holding and folding back the lower ply of the blank, and means for oscillating the swinging suction-box while the blank-support is rotating.

14. The combination, in devices for forming 105 the described funnel folds in the mouth ends of bellows-sided bag-blanks, of a rotatable blank-support, a stationary suction-box for sustaining the upper ply of the blank, a swinging suction-box mounted for oscillation on 110 the blank-support, and provided with a perforated suction-surface for holding and folding back the lower ply of the blank to form flattened triangular folds, means for oscillating 115 the suction-box while the blank-support is rotating, and means for doubling the said triangular folds to form the said funnel folds.

15. The combination, in devices for forming the described funnel folds in the mouth ends 120 of bellows-sided bag-blanks, of a rotatable blank-support, a stationary suction-box for sustaining the upper ply of the blank, a swinging suction-box mounted for oscillation on the blank-support, and provided with a perforated 125 suction-surface for holding and folding back a ply of the blank to form flattened triangular folds, means for oscillating the suction-box while the blank-support is rotating, and a movable reversing-blade mounted on the blank-support to coöperate with the swing- 130

ing suction-box in doubling the said triangular folds to form the said funnel folds.

16. The combination, in means for forming the described funnel folds in a paper-bag blank, of a rotatable blank-support, means for gripping one end of the blank to the support, a suction-box for sustaining the upper ply of the blank, a swinging suction-box mounted for oscillation in the blank-support and provided with a perforated suction-surface for holding and folding back the lower ply of the blank, means for oscillating the swinging suction-box while the blank-support is rotating, a reversing-blade having a defining edge substantially parallel to the axis of rotation of the swinging suction-box for reversing the fold-line 99, and holding the said fold-line in substantial coincidence with the said axis.
17. The combination, in means for forming the described funnel folds in a paper-bag blank, of a rotatable blank-support, means for gripping one end of the blank to the support,

a suction-box for sustaining the upper ply of the blank, a swinging suction-box mounted for oscillation in the blank-support and provided with a perforated suction-surface for holding and folding back the lower ply of the blank, means for oscillating the swinging suction-box while the blank-support is rotating, a reversing-blade having a defining edge substantially parallel to the axis of rotation of the swinging suction-box for reversing the fold-line 99, and holding the said fold-line in substantial coincidence with the said axis, and means for flattening the funnel folds of the blank.

In testimony whereof I have signed my name to this specification in the presence of two subscribing witnesses.

WILLIAM A. LORENZ.
